CORSET

Joseph J. Kispert, New Haven, Conn.

Application June 30, 1941, Serial No. 400,501

5 Claims. (Cl. 2-27)

This invention relates to apparel and more particularly to corsets, it being one object of the invention to provide a corset having improved front sections so formed and mounted that the corset will have compressing qualities when worn and tend to reduce and flatten the abdomen.

Another object of the invention is to provide the forward sections of the corset with inner flaps provided with interengageable fasteners for detachably holding the same in engagement with each other, the flaps being yieldably and adjustably mounted in such manner that when the corset is worn, strain will be applied to the flaps and a very good compressing action created.

Another object of the invention is to provide the front sections with inner flaps adjustably mounted through the medium of elastic lacings, thus creating the desired reducing pull along the front of the corset and, in addition, permitting renewal of the elastic pull exerting means when necessary.

Another object of the invention is to provide the corset with free meeting edge portions having soft and yieldable reinforcements to which hooks for engagement by lacing cords are secured, the hooks being disposed against the inner faces of said meeting edge portions where they will be out of the way and not liable to catch in portions of a garment worn over the corset.

Another object of the invention is to provide hooks so formed that the lacings may be easily engaged with them and not be liable to slip out of engagement with the hooks.

In the accompanying drawings:

Fig. 1 is a view looking at the outer face of the corset.

Fig. 2 is a view looking at the inner face of the corset.

Fig. 3 is a view showing the corset applied to a person.

Fig. 4 is a fragmentary view on an enlarged scale, looking at the outer face of one forward portion of the corset.

Fig. 5 is a view similar to Fig. 4, with the outer flap broken away and showing the manner in which the intermediate flap is laced to its mounting strip.

Fig. 6 is a view looking at the inner face of the forward portion of the corset shown in Fig. 4.

Fig. 7 is a view similar to Fig. 6, with the inner flap broken away.

Fig. 8 is a sectional view on an enlarged scale, taken on the line 8-8 of Fig. 4.

Fig. 9 is an enlarged view of one of the hooks carried by the intermediate flaps.

Fig. 10 is a side view of the hook.

Fig. 11 is an end view of the hook.

My improved corset, which is indicated in general by the numeral 1, has front sections 2, each of which is reinforced by a stay 3 consisting of a strip of thin resilient metal 4 enclosed in a fabric casing 5. The forward portion of each front section consists of inner and outer flaps 6 and 7 which are formed of fabric and secured along their inner side edges between the stay 3 and the body portion front section by stitching 8, as shown in Fig. 8. A strip 9 of fabric is also secured by the stitching 8, and upon referring to Fig. 8, it will be seen that the strip, which may be referred to as an anchoring strip, is disposed between the flaps 6 and 7 and free from the flaps except along its secured inner side edge. A stay 10 is stitched to the inner face of the strip 9 along the free side edge thereof, and eyelets 11 are mounted through the strip and the inner side edge portion of the stay. The free side edges of the inner and outer flaps 6 and 7 are reinforced by stays 12 and 13 and, referring to Fig. 8, it will be seen that the stay 12 consists of a resilient strip 14 encased in fabric 15 while the stay 13 is soft and pliable and consists of a core 16 of coarse fabric enclosed in a jacket 17 of finer fabric. The stay 12 is stitched against the front face of the flap 6 and the stay 13 is mounted within a pocket formed by a fabric strip 18 stitched against the rear face of the flap 7. Eyelets 19 are mounted through the lower portion of the flap 7 to receive laces 20, and, above these eyelets, there are provided hooks 21 which are mounted on the stay 13 and have their bills 22 overlapping the strip 18 rearwardly of the flap 7. By this arrangement, the hooks will have their bills in back of the flaps 7 when the corset is worn and they will be concealed and prevented from catching in a garment worn over the corset. The bills 22 of the hooks have their side portions bent to form lips 23 serving to guide the laces 24 into engagement with the hooks and also eliminating sharp edges which would cause the laces to be frayed and quickly broken when the laces are tightened. Stitching 13 is sewed through the stay 13 to reinforce the stay and the marginal portion of the flap to which the stay is applied and, by referring to Fig. 4, it will be seen that the stitching is so applied that it divides the stay into sections, each of which has a hook mounted thereon. This greatly strengthens the stay and prevents wrinkling thereof and not only eliminates likelihood of the hooks being torn loose from the stay, but also permits the stay to bend in all directions and makes the corset more comfortable.

as it may be laced right to the bottom of the abdomen and hold the abdomen compressed and uplifted without the lower end of the stay digging into the abdomen when a person wearing the corset is seated.

The intermediate flap 25 is formed of fabric of the same kind used for the inner and outer flaps and the anchoring strip 9. This flap 25 is provided along its inner side edge with a stay 26 which is stitched to the flap and eyelets 27 are mounted through the stay 26 so that the flap may be connected with the anchoring strip by a lacing cord 28 which is threaded back and forth through the eyes 11 and 27. This lacing cord 28 is formed of elastic fabric and while it normally holds the flap 25 close to the reinforced side edge of the anchoring strip, it permits the flap to be drawn away from the strip a limited distance. A stay 29 is stitched along the free side edge of the flap 25 within a pocket formed by a fabric facing strip 30. This stay has a core 31 consisting of a strip of resilient metal encased in fabric 32 and carries fastener members 33 and 34 for engagement with companion fasteners carried by the core of the stay for the other front section of the corset. A strip 35 of elastic fabric extends between the free side edge of the inner flap 6 and the intermediate flap 25, and, referring to Fig. 8, it will be seen that this elastic strip has one end portion sewed into place between the stay 12 and the free edge portion of the inner flap and its other end portion is stitched into the fabric casing of the stay 29. This elastic strip yieldably holds the free side edge portions of the flaps 6 and 25 to each other but permits the intermediate flap 25 to have movement toward and away from the free side edge of the inner flap 6.

When this improved corset is worn, it is applied about a person's waist and hips and secured as shown in Fig. 3. As it is applied, the fasteners 34 are first engaged with each other and then the fasteners 33 moved into engagement with each other. In order to do so, the flaps 25 must be brought toward each other and as they are shifted toward each other, the elastic laces 28 and the elastic strips 35 are stretched and thus tensioned so that they exert pull on the corset circumferentially of the person. The outer flaps 7 are then brought in toward each other and the laces 20 threaded through the eyes 19 and the laces 20 engaged with the hooks 21 and pull exerted to stretch the outer flaps transversely. As the laces are pulled to draw the flaps 7 toward each other, the laces 28 and the strips 35 contract and the inner flaps 6 and the intermediate flaps 25 are held smooth and in close contacting engagement with portions of the body against which they fit. A compressing action will thus be created and objectionable bulges eliminated. The fact that the hooks 21 are under the flaps 7, not only prevents them from catching in garments worn over the corset, but also imparts a smooth finish to the corset and prevents the hooks from showing through a dress. Since the hooks have their side portions bent to form the lips 23, the laces 24 may be easily engaged therewith and pull exerted to tighten the laces without fraying the laces. It will be understood that the laces 24 or the laces 20 may be first applied and tightened, pull then being alternately applied to the laces until the flaps have been stretched as much as desired. When the elastic laces 28 lose their elasticity, they can be easily removed and new laces substituted. The construction of the outer front closure per se including the flexible lacing

stays 13, is not being claimed herewith as it constitutes the subject matter of my co-pending application Ser. No. 490,353, filed June 10, 1943.

Having thus described the invention, what is claimed is:

1. A corset open along its front and having front sections free from each other, inner and outer flaps carried by the front sections, an anchoring strip mounted between inner side portions of the inner and outer flaps of each front section, an intermediate flap companion to each anchoring strip, elastic laces connecting the intermediate flaps with the anchoring strips, elastic strips connecting outer side edge portions of the inner flaps with outer side portions of the intermediate flaps, fastener members carried by the intermediate flaps for detachably holding the normally free side edges of the intermediate flaps in engagement with each other and close the front opening of the corset, laces for the outer flaps, and members carried by the free side edge portions of the outer flaps for engagement by the laces whereby the outer flaps may be drawn toward each other and the corset constricted about a person wearing the same, the elastic laces and the elastic strips being stretched when the intermediate flaps are connected with each other and applying transverse strain to the intermediate flaps to hold same smooth when the laces for the outer flaps are tightened to draw the outer flaps toward each other.

2. A corset open along its front and having front sections free from each other, inner and outer flaps carried by the front sections, an anchoring strip mounted between inner side portions of the inner and outer flaps of each front section, an intermediate flap companion to each anchoring strip, elastic laces connecting the intermediate flaps with the anchoring strips, elastic strips connecting outer side edge portions of the inner flaps with outer side portions of the intermediate flaps, fastener members carried by the intermediate flaps for detachably holding the normally free side edges of the intermediate flaps in engagement with each other and close the front opening of the corset, soft stays extending along the free side edges of the outer flaps and each having a core of fabric enclosed in a fabric casing, hooks carried by the stays, each hook having an attaching portion secured within the stay and a bill overlapping the inner face of the stay transversely thereof, and laces carried by the outer flaps for engaging the hooks and drawing the outer flaps toward each other into flat contacting engagement with the intermediate flaps when tightened.

3. A corset open along its front and having front sections free from each other, inner and outer flaps carried by the front sections, an anchoring strip mounted between inner side portions of the inner and outer flaps of each front section, an intermediate flap companion to each anchoring strip, elastic means adjustably connecting inner side edge portions of the intermediate flaps with outer side edge portions of the anchoring strips, means to releasably connect outer side edges of intermediate flaps with each other, and close the front opening of the corset, elastic connections between the outer edges of the inner flaps and outer side edge portions of the intermediate flaps, laces carried by the outer flaps at outer side edges thereof, and members carried

by the outer side edges of the outer flaps for engagement by the laces.

4. A corset open along its front and having front sections free from each other, inner and outer flaps carried by the front sections, an anchoring strip mounted between inner side portions of the inner and outer flaps of each front section, an intermediate flap companion to each anchoring strip, elastic means adjustably connecting inner side edge portions of the intermediate flaps with outer side edge portions of the anchoring strips, means to releasably connect outer side edges of intermediate flaps with each other and close the front opening of the corset, soft stays extending along outer side edges of the outer flaps, each stay consisting of a core formed of fabric tapes and enclosed in a fabric jacket, hooks mounted on the tapes and having bills overlapping inner faces of the stays transversely thereof, lines of stitching passing through the tapes and the jackets and extending back and forth across the same between the hooks to divide the stays into portions each carrying a hook, and laces carried by the stays for engagement with the hooks to draw the outer sections toward each other into flat contacting engagement with the

intermediate flaps when the laces are tightened.

5. A corset open along its front and having front sections free from each other, inner and outer flaps carried by the front sections, an anchoring strip mounted between inner side portions of the inner and outer flaps of each front section, an intermediate flap companion to each anchoring strip, elastic means adjustably connecting inner side edge portions of the intermediate flaps with outer side edge portions of the anchoring strips, means to releasably connect outer side edges of intermediate flaps with each other and close the front opening of the corset, stays extending along outer side edges of the outer flaps, the stays being formed of soft pliable material, hooks carried by said stays and having bills overlying inner faces of the stays, the bills of the hooks having side portions bent to form lips along side portions of the bills, and laces carried by the stays, the lips serving to guide the laces into engagement with the hooks and the laces serving to draw the outer flaps toward each other into flat contacting engagement with the intermediate flaps when tightened.
